Merrill M. Blackburn

ATTORNEY.

Patented Apr. 6, 1926.

UNITED STATES PATENT OFFICE.

WILLIAM P. HAGEDORN, OF DAVENPORT, IOWA.

SKID CHAIN.

Application filed June 1, 1925. Serial No. 34,087.

To all whom it may concern:

Be it known that I, WILLIAM P. HAGEDORN, a citizen of the United States, residing at Davenport, in the county of Scott, State of Iowa, have invented certain new and useful Improvements in Skid Chains, of which the following is a specification.

Generically my invention relates to improvements in construction and operation of skid chains and more specifically to the means for connecting the ends of the sides of such chains. Among the objects of my invention are to produce a construction of the character stated which can be applied to 10 automobile wheels without the necessity of placing the chains on the ground or on the wheels and then moving the car forward or backward until the chains can be fastened; to produce a device of the kind stated in 15 which a floating cross chain will automatically move into its proper position with the advancing movement of the wheel; to produce a device of the kind stated in which a floating cross chain will automatically move 20 into its proper position and be automatically locked therein; to provide an improved locking member for securing the ends of the side chains together; to provide in a structure of the character indicated an 25 improved hook and locking means; and such 30 further objects, advantages and capabilities as will later more fully appear and as are inherent in the construction disclosed.

My invention further resides in the combination, construction and arrangement of parts illustrated in the accompanying drawing and, while I have shown therein a preferred embodiment of my invention, I desire the same to be understood as illustrative only 35 and not as limiting said invention.

In the drawing annexed hereto and forming a part hereof, Fig. 1 is a side view of the connecting bar for the ends of one of the side chains of a skid chain; Fig. 2 is a plan view of the structure shown in Fig. 1; Fig. 45 3 is a fragmentary plan view similar to Fig. 2 but showing the end link of a cross chain just about to drop into the locking notch which holds said cross chain in properly adjusted position; Fig. 4 is a side view showing the link completely received by the holding notch; Fig. 5 is a transverse section approximately along the plane indicated by the line 5-5, Fig. 1; Fig. 6 is a perspective 50 view of one form of end link which is suitable for use with the cross chains; Fig. 7 is

a view similar to Fig. 4 but showing the use of a pivoted end hook instead of an end hook rigid with the side bar as shown in Figs. 1 to 55 4, inclusive; and Fig. 8 is a fragmentary plan view of a pair of side bars with chains attached.

Referring more in detail to these drawings, numeral 1 designates a connecting link or side bar designed for use upon the right side of a wheel. The corresponding link or bar for the left side of the wheel would be of the same shape except that the eye at the rear end will be offset to the opposite side 60 of the link and the chain receiving slot and hook at the opposite end will also be reversed, to face in the opposite direction. The laterally offset eye 2 has an opening 3 therein for the reception of an end link 4 of one of the side chains as will be readily understood. At the opposite side of the link 1 is a hook 5 adapted to receive a link of the other end of the side chain. A member 6, U-shaped in cross-section, is pivoted at 7 to the hook 5 and is provided with finger pieces 8 whereby it may be manipulated to open and closed position.

An ordinary cross chain is provided at its ends with suitable links 9, such, for example, as the one shown in Fig. 6 which has the eye 10 and the hook 11 arranged approximately at 90 degrees to each other, in order that the links of the chain may lie flat on the ground during operation. Of course it is understood that the shape and structure of the link 9 must vary according to the shape and structure of the cross chain used, the one shown being particularly adapted for a common chain now on the market. When these links 9 are applied to the ends of this chain, 85 the hooks 11 are closed up to prevent the detachment of the links from the ends of the cross chain. Slot 12 opens through the upper part of the link 1 into a slot 13 as shown. This device is so constructed that points 14 and 15 project on opposite sides of the slot 12, as shown most clearly in Fig. 2. Fig. 3 shows the purpose of these projecting points. From this figure it will be seen that the link 9, when it slides down the side link 1, will 90 engage the point 15 and will be prevented from going further. The outer side of the loop 10 will swing around past the point 14 and the link will then drop through the notch or slot 12 into the slot 13 and will be held therein by the projecting points 14 and 15, as will be evident from Figs. 4 and 7.

The side bars or links 1 are preferably substantially flat on the side toward the tire, are broad as indicated at 16, across the top edge, and are preferably hollow ground or substantially flat upon the outside as indicated at 17, being narrow at the bottom.

As indicated in Fig. 7, the hook 5 is dispensed with and the loose hook 18 is pivotally connected as at 19 to the end of the 10 side bar 1. This latter is suitably enlarged as shown at 20 and slotted as indicated at 21 for the reception of the hook 18. This latter carries a suitable latch element 6 as in the previously described construction.

15 In use, the chains are placed over the top of the tires with the ends carrying my improvement at the rear side of the wheel, the vacant ends of the side chains being at the front, as will be understood. The floating cross chains will be at the rear ends of the side bars 1, as shown in Fig. 1 and the hooks 5 or 18 can then be connected to the free ends of the side chains, the latches 6 being closed, as will be readily understood.

20 Having thus applied all of the chains, the driver gets into his car and starts up as usual. As the wheels roll forward and the side bars 1 rise toward the position indicated in Fig. 4, the cross chains slide downwardly, carrying the links 9 toward the slots 12. When one side of the link 9 strikes the abutment 15 the link swings around past the point 14 and drops into the notch 12. Having once been received

25 in the slot 13 the points 14 and 15 prevent accidental disconnection of the link 9 which is bound to remain always within the slot 13. It will thus be understood that the cross chain automatically seats itself in its proper place and prevents undue slack in the side chains which sometimes results when the cross chain is missing. It will also be understood that, when the car is moving forwardly or backwardly, the cross chain must necessarily remain in its proper position, as is not true when the cross chains are pulled into place and held there by gravity alone or by means of springs.

Having now described my invention, I 50 claim:

1. In a skid chain, means rendering it possible to attach the chain to a wheel, comprising a pair of bars for connecting the ends of the side chains, in combination with a floating cross chain slideable on the bars, said bars having longitudinally arranged slots at one end whereby the ends of the cross chain are received and held in proper operative position during the normal operation of the wheel. 55

2. In a structure of the character described, a pair of spaced side chains, cross chains spaced at intervals along the side chains, bars connecting the ends of the side chains, said bars each having adjacent one end a diagonally arranged slot for the reception of a cross chain, and a cross chain having its ends slideable on the bars and receivable in the slots. 60

3. In a skid chain having a side chain, 70 a curved bar for connecting the ends of the side chain, said bar having in its upper surface a diagonal slot for the reception of a link of a cross-chain, a longitudinally arranged slot within the bar and connected to the diagonal slot, and a cross-chain having a link surrounding the curved bar, slideable thereon, and receivable in the slots. 75

4. In a skid chain having a side chain, a curved bar for connecting the ends of the side chain, said bar having adjacent one end a diagonal slot for the reception and holding of a cross chain, and a cross chain having an end link slideable on the curved bar and receivable in the said slot. 80

5. In a skid chain having a pair of side chains, bars for connecting the ends of the respective side chains, said bars each having adjacent one end locking means for the reception and holding of a cross chain, a cross chain connecting said bars and having a link at each end slideable on the bars, said locking means having an opening therein requiring the end link of the cross chain to turn diagonally of the bar to enter 90 the locking means. 95

In witness whereof, I hereunto subscribe my name to this specification.

WM. P. HAGEDORN.
